TOY TRANSPORTATION SYSTEM

John J. Clark, Clinton, Iowa

Application February 25, 1935, Serial No. 8,031

6 Claims. (Cl. 46—48)

My invention relates to toy transportation systems in which miniature vehicles may be caused to travel along a track in almost any direction, by 5 tilting the base on which the track is mounted, whereby the particular portion of the track in which the vehicle is momentarily located, may be inclined downwardly to cause the vehicle to travel by gravity, the tilting positions of the base being changed to provide for continuous movement of 10 the vehicle, as where for example it travels in a closed circuit or back and forth over the same stretch of track. The vehicles may be miniature railway cars running on two rails representing a railroad track, an automobile running on rails 15 or in a trough, aeroplanes, zeppelins and aerial torpedoes running on a single rail or a double rail above or below the same. The traveling objects may also constitute representations of birds, flying insects and the like.

20 The object of the invention is to provide a toy having a wide range of adaptation and use, whereby the imagination of the child using it may be stimulated and satisfied by the very extensive possibilities suggested by the moving object.

25 A further object is to provide a device of this character in which the vehicles or other moving objects may travel not only along a plane surface but up and down grade, as for example where a train is made to climb to the top of a mountain 30 and then travel downwardly and around the same in a gradually enlarging series of loops.

Various other objects relate to the details of construction, whereby the railway track or a monorail is supported above the base.

35 In the accompanying drawings:

Fig. 1 is a perspective view of a railway system in which a certain stretch of track encircles a mountain;

Fig. 2 is a side elevation thereof;

Fig. 3 is a front elevation of a modified form of the invention in which the representation of a mountain is shown on a flat vertical surface;

Fig. 4 is a side elevation thereof;

Fig. 5 is a top plan view of a further modification in which the track has the form of a monorail on which a car or an aeroplane may travel;

Figs. 6, 7 and 8 are views of detailed structural features, and

Figs. 9-12 illustrate various modifications.

50 In the toy illustrated in Figs. 1 and 2, a base 10 is provided which may be in the form of a board or any sheet of flat material, metal or composition, or which may be in the form of an open frame with suitable transverse members. The base is mounted on a support 11 which enables it

to rock in any direction. This support is curved not only longitudinally but transversely, whereby it presents a concave surface facilitating the rocking of the base back and forth, sidewise or in any desired combination of these movements. The base may have a handle or handles 12 projecting therefrom for the child to take hold of although such handles are not essential. Said handles, where provided, may rest on the floor or table and thus steady the device and prevent accidental tipping thereof when it is not in use.

5 10 A railroad track 13 is mounted on the base and is shown as a loop 14 at one end of the base, provided with switches 15, this loop surrounding a toy city or any group of small houses, buildings or the like. At the other end, a railway station or any other desired building may be surrounded by another loop of track. Between the two ends of the board, in the arrangement illustrated, there is mounted an object of considerable elevation, 15 which may have the form of a mountain. The track leading from the left hand side of the loop 14 may approach the mountain on a level and ascend the inclined side thereof abruptly, circling round and round the mountain in gradually enlarging loops 16 to the bottom. Preferably, however, the track leading to the mountain ascends a trestle 17. The tracks leading from the loop 14 to the mountain, preferably cross each other as is also the case with the tracks beyond the mountain. 20 Also, the tracks, which are substantially parallel to each other on the two sides of the board, may each pass up and down over a hump or trestle 18, 19, if desired. The arrangement is such that a locomotive, car or a complete train 19 may start 25 at either end of the board, ascend the mountain, descend the same and then travel to the other end of the board and back to the starting position. By operating the various switches 15, the train may travel round and round the loop several times, 30 or may be made to ascend the mountain by running round and round the loops and descend along the trestle. The arrangement described is merely 35 illustrative of the great variety of possibilities.

Instead of a train, it will be understood that an 40 automobile or any other wheeled vehicle may occupy the tracks.

45 In the form of toy shown in Fig. 3 and Fig. 4, the base is mounted on double rockers 20, 20, as illustrating a modified support, although the convex support previously described may, of course, be employed. The double rocker imparts transverse stability to the toy, although it can be rocked transversely by tipping it about one rocker or the other. The mountain 21, in this case, is 50 55

made of flat sheet material such as wood, metal or cardboard, preferably the latter where the toy is intended to be small and inexpensive. The two sides are printed or otherwise decorated to simulate a mountain or any other desired scenery. The track, to which the same reference numeral has been applied as in Figs. 1 and 2, may be supported in various ways, as on the base or on the vertical sheet of material representing the mountain. For example, brackets 22 may project from opposite sides of the sheet to support the tracks, which at the ends curve around to join the length of track on the other side. These curves are somewhat enlarged where the lengths of track on the opposite sides are fairly close to the mountain.

In Fig. 5 the general layout may be assumed to be the same as in Figs. 1 and 2, except that a single rail or monorail 23 is used to guide a depending car 24 or an aeroplane 24', the latter being secured to the rail in any one of a number of different ways, whereby its travel may be directed by the rail.

Where the vehicles or other moving objects are light as where made of cardboard, for example, or as in the case of a toy aeroplane which is light in construction in any case, the weight and inertia of the wheels are relied on to assist the travel of the vehicle.

In Fig. 6, I have shown the wheel as consisting of a pulley or sheave 25, with arms 26 having a weight 27 at the lower end of one of them, to which the object is attached in any suitable manner, or it may be mounted at the top of said arms.

In Fig. 7, I have shown a grooved ball 28 with a similarly weighted arm to which any suitable object may be attached. The grooved ball may run on any number of different types of track. The one shown is of inexpensive construction, consisting of a strip of cardboard 30, reinforced with thin sheet metal such as tin 31, bent over the upper part of it and held in place by indentations 32 struck in the metal. The track may be supported by brackets 33 of cardboard, metal or other material, glued or otherwise secured to the vertical strip 30. This form of track may be bent to assume any desired curves and is light and stiff.

In Fig. 8, I have shown a modified form of carrier, i. e. a pulley 34 having a U shaped metal member 35 with its parallel arms depending below the pulley to the top of which U shaped member, preferably the vehicle or other light object is attached. This small pulley may run on a small wire 36 embraced by small clamping members 37 which are in turn supported on a light metal channel 38 suitably bent or curved and fastened to a convenient support such, for example, as the mountain shown in Fig. 5. The depending arms of the supporting member 35 clear the vertical part of the support 38.

In Fig. 9, I have shown a ball 39 having an axle 40 and a sheet metal bracket 41 to which is secured an object such as 42, which is to be drawn along by a ball as it rolls in a grooved or trough shaped track 43 such as shown in Fig. 10, for example. Two modified forms of track 44, 45 are shown in Figs. 11 and 12 respectively. These tracks, like the others, may be grooved so that the ball may be made to ascend or descend some substantial elevation or travel around and around some object like a mountain, a cylindrical tower or any other elevated structure.

It will be apparent that a great number of changes and combinations may be made in the

track supporting devices and other special parts heretofore described and that the vehicles may include roller coasters, sleds, toboggans, boats and almost any representation of a traveling object or animal.

I claim:

1. A toy transportation system comprising a base, a rocking support therefor, a representation of a mountain on said base, a length of track on said base extending to said mountain, up the side thereof and down and around the same in loops, and a vehicle on said track, whereby said base may be rocked to cause any portion of said track occupied by said vehicle to be inclined downwardly temporarily and thus propel said vehicle continuously along successive portions of said track and cause it to appear to travel up said mountain, down which it may travel without further manipulation of said base.

2. A toy transportation system comprising a base, a rounded support therefor permitting rocking in any direction, a representation of a mountain on said base, a length of track on said base extending to said mountain, up the side thereof and down and around the same in loops, a closed loop of track connected by switches to said length of track, and a vehicle on said track, whereby said base may be rocked to cause said vehicle to appear to travel up the mountain and down the same, said switches permitting further travel of said vehicle around said loop.

3. A toy transportation system comprising a base, a support therefor convex in two directions at right angles to each other, a representation of a mountain on said base, a length of track on said base, a trestle leading from the plane of the base to the upper part of said mountain and down and around the same and a vehicle on said track whereby tilting of said base in the proper direction will cause the same to travel throughout the length of said track.

4. A toy transportation system comprising a base, a rocking support therefor, a representation of a mountain on said base consisting of a vertical sheet of flat material, a length of track on said base extending from the surface of said base to the upper part of said vertical sheet and down around both sides thereof, brackets on opposite sides of said sheet supporting said track in nearly parallel spans connected at the ends by curved portions and a vehicle on said track adapted to travel throughout the length thereof when said base is rocked.

5. A toy comprising a base, an elongated support therefor curved longitudinally and transversely, a structure on said base extending upwardly therefrom, a railway track supported by said structure in a generally descending slope, and a wheeled car on said track, whereby said car may be caused to appear to ascend said track by gravity by rocking said base, and may descend by gravity when said base is stationary.

6. A toy comprising a base, an elongated support therefor curved longitudinally and transversely, a structure on said base extending upwardly therefrom, a track supported by said structure in a generally descending slope, and a light vehicle on said track having at least one heavy wheel to provide the necessary momentum, whereby said car may be caused to appear to ascend said track by gravity by rocking said base, and may descend by gravity when said base is stationary.

JOHN J. CLARK.
